UNITED STATES PATENT OFFICE.

ABRAHAM GARBEIL, OF PHILADELPHIA, PENNSYLVANIA, AND ALBERTO CIMOROSI,
OF GLASSBORO, NEW JERSEY.

EXPLODIBLE PAPER TOY.

1,199,776.

Specification of Letters Patent.

Patented Oct. 3, 1916.

Application filed March 22, 1916. Serial No. 85,763.

To all whom it may concern:

Be it known that we, ABRAHAM GARBEIL, a citizen of the United States, residing at Philadelphia, county of Philadelphia, and State of Pennsylvania, and ALBERTO CIMOROSI, a subject of the King of Italy, residing at Glassboro, county of Gloucester, and State of New Jersey, have invented certain new and useful Improvements in Explosible 10 Paper Toys, of which the following is a specification.

Our invention relates to improvements in 15 explosible paper toys, the object of the invention being to provide a paper toy which represents submarine warfare and gives the impression of a torpedo fired from a submarine and blowing up a larger vessel.

A further object is to provide a toy of 20 the character described which can be manufactured and sold at an extremely low price, and which will most efficiently perform the functions for which it is intended.

With these and other objects in view, the 25 invention consists in certain novel features of construction and combinations and arrangements of parts as will be more fully hereinafter described and pointed out in the claims.

In the accompanying drawings: Figure 1 30 is a view in side elevation illustrating one form of our improvements. Fig. 2 is a view in transverse section on the line 2-2 of Fig. 1. Fig. 3 is a view in longitudinal section. Fig. 4 is a view in transverse section 35 on the line 4-4 of Fig. 1. Fig. 5 is a view in side elevation illustrating a modification. Fig. 6 is a view in section on the line 6-6 of Fig. 5. Fig. 7 is a view in side elevation 40 illustrating another modification, and Fig. 8 is a view in section on the line 8-8 of Fig. 7.

Referring particularly to Figs. 1, 2, 3, and 4, 1 represents the base of our improved 45 toy which is composed of a single paper blank, the base 1 extending throughout the length of the toy and having at its respective ends triangular casings 2 and 3. The casing 2 is appreciably smaller than the casing 3, but both casings are constructed alike. 50 They each form an integral part of the base strip 1, and are folded on the fold lines 4, 5, and 6, and are provided with tongues 7 which are projected through slots 8 in the base 1 to hold the casings in triangular formation. These casings are reinforced by

flaps or tongues 9, integral with the base 1, and folded inside of the casings as shown clearly in Figs. 2 and 4. On the base strip 1, a tube 10 is secured. This tube 10 is preferably of paper formed in any approved 60 manner, and provided near one end with an angular crimp 11 which divides the tubes into a relatively long fuse 12 and a relatively short explosive compartment 13. The fuse 12 is formed by a line of powder or 65 suitable chemical which when ignited burns with a hissing sound until the explosive compartment 13 is reached when there is a loud report from the explosive compartment and a shattering of the casing 3. On 70 the casing 2, we preferably locate the representation of a submarine, and on casing 3 the representation of a ship, the latter shown sinking in the water as a result of a torpedo explosion, hence when the fuse is 75 lighted, the toy gives the realistic appearance of a submarine discharging a torpedo and blowing up a ship.

In the modification shown in Figs. 5 and 6, a cardboard sheet 14 is supported by a 80 prop 15, which extends through a slot 16 in the sheet 14. On the back of the sheet 14, we secure a tube 10 corresponding to the tube 10 above described, and on the front of the sheet 14, we show representations of 85 the submarine and ship.

In the modification shown in Figs. 7 and 8, 17 represents a cardboard sheet having a supporting tongue 18 bent from a central portion 19 of the sheet 17. The sheet 17 is 90 cut so that one end 20 thereof is relatively small, and the other end 21 is relatively large, and these end portions 20 and 21 contain the representations of a submarine and ship respectively. On the back of the 95 sheet 17, we secure a tube 10 corresponding to the tube of the forms above described.

It will be noted that with all forms of 100 our invention, the idea is conveyed of a submarine in the act of blowing up a ship, and the result of the explosion is the destruction of the toy, so that in appearance and effect, the idea of submarine warfare is carried out.

Various other slight changes might be 105 made in the general form and arrangement of parts described without departing from our invention, and hence we do not limit ourselves to the precise details set forth, but consider ourselves at liberty to make such 110

changes and alterations as fairly fall within the spirit and scope of the appended claims.

Having thus described our invention, what we claim as new and desire to secure by Letters Patent is:

1. An explodable toy having a front portion representing a submarine and a larger vessel and composed of fragile material, a rear portion extending from said front portion and forming means for supporting the front section in a raised position, a container in which an explosive mixture is located, said container being positioned between the front and rear portions, and a fuse connected to said container, substantially as described.
2. An explodable toy having a front portion representing a submarine and a larger vessel and composed of fragile material, a rear portion extending from said front portion and forming means for supporting the front section in a raised position, a container in which an explosive mixture is located, said container being positioned between the front and rear portions, a fuse connected to said container, said fuse extending from a point outside of said front and rear portions whereby it may be readily lighted, substantially as described.
3. An explodable paper toy, comprising a

base strip, casings on the base strip, an explosive mixture inside of one casing, and a fuse inside the other casing communicating with the explosive mixture, substantially as described.

4. An explodable paper toy, comprising a base strip, triangular casings on the respective ends of the base strip, one relatively large and the other relatively small representing a ship and submarine respectively, and a tube secured on the base strip and extending under both casings, said tube containing an explosive mixture in the relatively large casing, and a line of fuse in the relatively small casing communicating with the explosive mixture, substantially as described.

5. A paper toy, comprising a base strip, triangular casings on the respective ends of the base strip, one relatively large and the other relatively small representing a ship and submarine respectively, substantially as described.

In testimony whereof we have signed our names to this specification in the presence of two subscribing witnesses.

ABRAHAM GARBEIL.
ALBERTO CIMOROSI.
